WELL DRILLING APPARATUS

Reuben Richard Schweitzer, Norfolk, Va., assignor to Layne & Bowler, Incorporated, Memphis, Tenn., a corporation of Delaware

Application February 24, 1941, Serial No. 380,089

5 Claims. (Cl. 255—73)

This invention relates to certain new and useful improvements in well drilling apparatus, and particularly to an improved construction of guide barrels for drill bits.

It is desirable for the well hole to be drilled with accuracy and with as little deviation as possible. Owing to variations in strata, ordinary drill bits, following the path of least resistance, cut unevenly and often cause the well hole to seriously deviate, and such deviation often seriously impedes or prevents handling of the casing.

In such drilling removal of the tools is often difficult and even impossible of accomplishment requiring abandonment of the well, because of the tendency of the cuttings to settle above the drilling apparatus, and also because of the tendencies of the mud fluid, often necessarily used to choke off porous formation or to assist in discharge of cuttings, to form a "filter cake" on the well wall, creating what is often termed by drillers a "squeeze" which freezes the tools against removal.

The principal object of this invention is to provide a well bit which will minimize deviation from the vertical in drilling a well.

A further object is to provide such a bit with an elongated guide barrel or cylinder having very small clearance from the wall of the well, and having means carried by the barrel for preventing closure of such clearance.

A further object is to provide means for weighting such a barrel to assist drilling.

A further object is to provide well drilling apparatus having the drill rod or pipe weighted adjacent its lower end.

A further object is to provide at the upper end of the guide barrel reaming means for enlarging the drill hole, primarily to increase clearance of the barrel and loosen up or cut through the accumulations of cuttings, filter cake and the like above the barrel and free same for removal.

The means by which the foregoing and other objects are accomplished and the manner of their accomplishment will readily be understood from the following specification on reference to the accompanying drawing, in which:

Fig. 1 is a side elevation of my well drill in use-position in a partially cut well hole; and

Fig. 2 is a similar fragmentary view, on an enlarged scale, with portions broken away showing details of the construction.

Referring now to the drawing in which the various parts are indicated by numerals:

11 is a rotatable drill pipe or stem around the lower portion of which is secured a hollow guide barrel or shell 13, which is of considerable length relative to the diameter of the well hole, as say twenty feet for a drill hole of eighteen inch diameter. The diameter of the guide barrel is preferably such that only a very slight annular clearance 12 is provided between it and the wall 15 of the drill hole. Thus for a drill hole of a diameter of eighteen inches the diameter of the guide barrel would preferably be seventeen and one-half inches, minimizing the possibility of variation in the line of drilling. Guide barrel 13 is concentric with drill pipe 11 and is carried by an upper annular disc 17 and a lower annular disc 19, which are respectively secured, preferably by welds 14, 16, 18, and 20, to both drill pipe 11 and the inside of barrel 13. Upper disc 17 is provided with a filling hole or holes 21, adapted for receiving weighting material, as concrete 22. Any other suitable weighting material however, as sand, or barite may be introduced into barrel 13 as desired. Disc 19 is secured to the barrel and the drill pipe adjacent the lower end of the barrel, and extending below disc 19 is a barrel skirt 23, which is serrated to provide teeth 25, which are preferably and usually faced with hardened cutting material to form grinding or cutting edges.

30 Drill pipe 11 extends longitudinally through barrel 13 and protrudes below teeth 25. Depended from the lower end of drill pipe 11 is a drill bit 27, which is removably secured to the drill pipe, the inner surface of the lower end of the drill pipe preferably being threaded as at 31 to receive the shank of the bit, which is provided with complementary threads. Drill pipe 11 is preferably hollow and is used to carry water forced downward for flushing chips, cuttings, and other detritus from the drill hole as work progresses. Drill bit 27 is provided with a central passage 33, and discharge ports 29, the flushing water discharging downward through passage 33 and ports 29, additional velocity being imparted by the relative restriction of size of the ports.

Carried by and secured to the upper portion of barrel 13, are a plurality of reamer blades 35, which are preferably beveled as at 37, and are preferably rigidly secured along the bevel to the barrel. The bevels 37 are preferably long bevels, and provide a gradual outward flaring of reamer blades 35 as they extend upwardly, the maximum flare being achieved substantially at the top of barrel 13. Reamer blades 35 may be bent inwardly as at 39 to form spacer portions 40, the

inner ends of which are rigidly secured to barrel 13 as at 41. It will be understood that while this inward bending of the reamer blades is preferred practice, providing the most efficient manner of forming the reamer blades, they may be spaced and secured otherwise as for instance by interposing independent members which may be secured as at 39 and 41. Reamer blades 35 are preferably provided with cutting edges 43, of usual and well known commercially available material, and are adapted to enlarge the drill hole, and by their tapering contact with the walls of the drill hole assist materially in preventing wobbling of barrel 13 or deviation of bit 27. 45 are braces which preferably form upward and inward continuations of the reamer blades and may be similarly provided with cutting edges, and are of primary importance in cutting through and loosening up accumulations of cuttings, filter cake or other obstructions which resist removal of the apparatus after drilling. They are preferably secured to the ends of the reamer blades and extend upwardly therefrom and inward toward the drill pipe to which they are also secured, as by welding.

In construction of my improved drilling apparatus, disc 19 is secured to drill pipe 11, preferably by welds 18, on both sides of the disc. Apertured upper disc 17 is similarly secured as by welds 16 to the drill pipe.

Guide barrel 13, comprising a hollow shell, may be positioned either before or after the reamer blades 35 are secured thereto, but in either case barrel 13 is secured to the outer edges, respectively, of discs 17 and 19, preferably by welds 14 and 20. Teeth 25 are formed in barrel skirt 23, and are preferably faced with hard material of some of the well known commercial types.

Reamer blades 35 are preferably formed of integral rectangular bars, the edges of which are similarly faced in usual manner to provide hardened cutting edges 43. The upper ends of the bars are bent inward at 39 to provide shallow upper end spacers and the bars extend downward from such spacers along the exterior of barrel 13. The lower ends of the bars are preferably beveled to form the long tapers 37, this beveling usually being accomplished by burning the bars down on an angle, although it may be accomplished otherwise.

The bevels 37 are formed to provide gradual flaring of the reamer blades 35 away from barrel 13, the flare reaching its maximum at bend 39, adjacent the top of barrel 13.

In securing blades 35 to barrel 13, the inner end of the spacer 40 of each reamer blade 35 is secured, preferably by welding, as at 41, to barrel 13 adjacent its top. The reamer blade is extended downwardly therefrom so that bevel 37 contacts and lies along an intermediate portion of the exterior of barrel 13. The lower end of each blade 35 is secured to barrel 13 by securing the bevel portion 37 to the barrel as by welding along the length of bevel, although spot welding, as at the top and bottom of the bevel, is satisfactory, as well as numerous other methods.

After blades 35 are secured to barrel 13 as described, and barrel 13 has been secured to drill pipe 11, the additional braces 45 may be used, additionally securing barrel 13 to drill pipe 11. The lower ends of braces 45 are rigidly secured to the upper ends of blades 35, and their upper ends to drill pipe 11, preferably by welding.

Bit 27 is screwed into engagement with 75

threaded portion 31 of the drill pipe, and extends well below the teeth 25. Suitable weighting material, as concrete 22, may be introduced into barrel 13 through opening 21, in such quantity as may be desired. Several materials, particularly barite, because of its high specific gravity, have been found to be highly satisfactory for weighting and may be substituted for concrete.

When drilling is begun, due to the arrangement which has been herein described, drill bit 27, being depended below barrel 13, may be immediately used to drill even the most shallow of holes. As the extra weight is carried in barrel 13 it is also immediately above the bit, and is available even in a shallow hole. After drilling passes the preliminary stages, the length and diameter of barrel 13 are such that a deviation from the line of drilling is substantially prevented. In addition, since weighted barrel 13 is placed adjacent bit 27, the weight is at the bottom of the drill pipe 11 and this is highly desirable for keeping the drill hole straight, as its depth increases, and lengthening of the drill pipe is necessary for operation.

25 During drilling water is forced downward through drill pipe 11, and discharges downwardly through passage 33 and ports 29 of bit 27, for flushing chips, etc., from the drill hole. This flushing water and detritus carried thereby discharges upwardly through the minor annular clearance 12 between barrel 13 and the wall 15 of the drill hole, and subsequently discharges at the surface.

30 The relatively minor amount of clearance affords an opportunity for discharging refuse to clog as it discharges upwardly, particularly as it reaches the lower end of the barrel and enters the minor annular clearance 12. It is for this reason that barrel skirt 23 is preferably serrated to form teeth 25. Teeth 25, upon drilling rotation of the apparatus, serve to grind and cut away any mass that may accumulate at the point of entrance to the annular clearance space 12, thereby preventing closure of the clearance space, and permitting passage of only those materials whose size is such as to readily be discharged upwardly with the flushing waters. It will be understood that teeth 25 may be formed in other manner than as shown without departing from my invention.

50 As drilling progresses downward, reamer blades 35 carried by the upper end of barrel 13 engage wall 15 and enlarge the drill hole to the desired size, and by their tapering contact with well wall 15, firmly hold the barrel 13 and bit 27 in position without lateral displacement. Reamer blades 35 are spaced apart around barrel 13 and do not impede the upward discharge flow of the flushing water.

60 After drilling has been completed, the drill pipe and attached barrel and bit are raised from the well. If minor accumulations only of filter cake and cuttings exist, the braces and reamer blades pull through and removal is accomplished. Ordinarily however it is necessary to rotate the drill pipe and through the barrel to rotate the braces and blades and loosen the cuttings and/or filter cake, to permit such removal; pumping of fluid through the drill pipe usually also being continued to effect the removal of such loosened materials.

65 It will be understood that, while barrel 13 has been herein described as hollow, it may be solid, furnishing thereby the desired additional weight. The barrel has also been described as being se-

cured adjacent its upper end to drill pipe 11 through apertured disc 17. It will be understood that the means for securing the upper portion of the barrel are not to be limited to an apertured disc but other suitable means may be substituted therefor. Thus, for example, radial arms might be employed without departing from my invention. It will also be understood that bit 21 need not be depended any appreciable distance below barrel 13, but may be secured to drill pipe 11 at such distance below the barrel as is desired.

I claim:

1. In an assembly for drilling a well which includes a rotatable drill pipe and a drill bit depended therebelow, means for guiding said bit during drilling which includes, in combination, a barrel, secured around said drill pipe, having a diameter less than the diameter of said bit with an annular clearance between said barrel and the wall of said well; and well-contacting means carried by the upper portion of the length of said barrel, comprising a plurality of arms secured to said barrel intermediate its length, and connected to the periphery of the top of said barrel and spaced therefrom, said arms being adapted to wedgingly contact said well wall to prevent sway of the upper portion of said barrel, and upon rotation to taperingly enlarge said well adjacent the upper portion of said barrel to facilitate subsequent removal of said assembly from said well.

2. In an assembly for drilling a well which includes a rotatable drill pipe and a drill bit depended therebelow, means for guiding said bit during drilling which includes, in combination, an elongated cylindrical barrel, secured around said drill pipe, having a diameter slightly less than the diameter of said bit and adapted to closely fit said well with a minor annular clearance only between said barrel and the wall of said well; and well-contacting means carried by the upper portion of the length of said barrel, comprising a plurality of arms secured to said barrel intermediate its length, said arms extending upwardly from said intermediate securing, and outwardly from the surface of said barrel, and being connected to the periphery of the top of said barrel and spaced therefrom, said arms being adapted to wedgingly contact said well wall to prevent sway of the upper portion of said barrel, and, upon rotation, to taperingly enlarge said well adjacent the upper portion of said barrel to facilitate removal of said assembly from said well.

3. An assembly for drilling a well which includes a rotatable drill pipe, adapted to carry fluid downward into said well for flushing detritus therefrom; a drill bit depended therebelow; an elongated guide barrel secured around the lower portion of said drill pipe, said guide barrel having a diameter slightly less than the diameter of said bit to closely fit said well, with a minor annular clearance only between said barrel and the wall of said well, to permit said fluid and detritus to discharge upwardly through said annular clearance; and means for facilitating the removal of said assembly from said well which in-

cludes a plurality of arms carried by the upper portion of the length of said barrel, secured to said barrel intermediate its length, said arms extending upwardly from said intermediate securing and outwardly from the surface of said barrel, and being connected to the periphery of the top of said barrel and spaced therefrom, said arms being adapted on assembly rotation to taperingly enlarge said well adjacent the upper portion of said barrel, and a plurality of stirrers secured to the top of said barrel, extending upwardly from said barrel top and inwardly toward said drill pipe, and being secured to said drill pipe, and adapted on assembly rotation to agitate said fluid and detritus carried thereby.

4. An assembly for drilling a well which includes a rotatable drill pipe adapted to carry fluid downward into said well for flushing detritus therefrom; a drill bit depended therebelow; an elongated cylindrical guide barrel secured around the lower portion of said drill pipe, said guide barrel having a diameter slightly less than the diameter of said bit to closely fit said well, with a minor annular clearance only between said barrel and the wall of said well to permit said fluid and detritus to discharge upwardly through said annular clearance; and means for facilitating the removal of said assembly from said well which includes a plurality of teeth formed in the lower end of said barrel, said teeth being adapted to grind and disintegrate masses of detritus approaching said annular space, a plurality of arms, carried by the upper portion of the length of said barrel, secured to said barrel intermediate its length, said arms extending upwardly from said intermediate securing, and outwardly from the surface of said barrel, and being connected to the periphery of the top of said barrel and spaced therefrom, said arms being adapted on assembly rotation to taperingly enlarge said well adjacent the upper portion of said barrel, and a plurality of stirrers secured to the top of said barrel, extending upwardly from said barrel top and inwardly toward said drill pipe, and being secured to said drill pipe, and adapted on assembly rotation to agitate said fluid and detritus carried thereby to minimize deposit thereof on said barrel top.

5. In an assembly for drilling a well, which includes a rotatable drill pipe and a drill bit, means for guiding said bit during drilling which includes, in combination, a barrel secured around said drill pipe; and well-contacting means, carried by the upper portion of the length of said barrel, said means being secured to said barrel intermediate its length, and connected to and flared from said barrel adjacent its upper end, said means being adapted to wedgingly contact said well wall to prevent sway of the upper portion of said barrel, and, upon rotation, to taperingly enlarge said well adjacent the upper portion of said barrel to facilitate subsequent removal of said assembly from said well.

REUBEN RICHARD SCHWEITZER.
